UNITED STATES PATENT OFFICE.

WILLIAM C. FARNUM, OF ARLINGTON, VERMONT, ASSIGNOR TO UNION TYPEWRITER COMPANY, OF JERSEY CITY, NEW JERSEY, A CORPORATION OF NEW JERSEY.

TYPE-WRITING MACHINE.

SPECIFICATION forming part of Letters Patent No. 752,215, dated February 16, 1904.

Application filed November 20, 1901. Serial No. 83,011. (No model.)

To all whom it may concern:

Be it known that I, WILLIAM C. FARNUM, a citizen of the United States, and a resident of Arlington, in the county of Bennington and State of Vermont, have invented certain new and useful Improvements in Type-Writing Machines, of which the following is a specification.

My invention relates to a feed mechanism for platens of type-writing machines whereby the platen may be rotated independently of the usual line-spacing mechanism thereof in order that any point on the paper may be brought to the printing-line without adjusting the paper on the platen.

The object of my invention is to provide a simple and efficient device of the character specified; and to these and other ends, which will hereinafter appear, the invention consists in the novel arrangement and combinations of parts to be hereinafter described and claimed.

In the accompanying drawings, wherein like reference characters designate corresponding parts in the various views, Figure 1 is a top view of a platen and platen-frame, showing the application of the device which constitutes the subject-matter of my invention. Fig. 2 is an enlarged fragmentary longitudinal sectional view taken on the line $\alpha\alpha$ of Fig. 5. Fig. 3 is a detail edge view of portions of the mechanism to be hereinafter described. Fig. 4 is an enlarged transverse sectional detail view of the device, the section being taken on the line yy of Fig. 2 and looking in the direction of the arrow in said figure. Fig. 5 is an end view of the parts shown in Fig. 1, the view looking toward the right-hand end of the platen.

The invention is shown in the accompanying drawings as applied to the platen and platen-frame of a No. 6 Remington machine, it being understood that various of the paper-feeding instrumentalities have been omitted.

In the drawings, 1 indicates a platen-frame in which a platen 2 is mounted to rotate. The platen may be provided with the usual finger-wheel 3 at the left-hand end thereof. The platen 2 is rigidly secured to the platen-shaft

4 by any suitable means, and the right-hand end of the platen-shaft 4 projects beyond the platen-frame and is headed at 5, and thus prevents an outward movement of certain of the parts. The head on the shaft is preferably obtained by a headed screw, the stem of which is received in a threaded opening in an end of the shaft, the head of said screw being the head 5. Loosely mounted upon the shaft 4 is a sleeve 6, which is limited against longitudinal movement on the shaft by a collar 7 thereon and a gear-wheel 8, which is secured to the shaft by a screw 9. The sleeve 6 has secured thereto a line-spacing wheel 10, the sleeve and wheel being united by a feather 11. Rigidly secured to the sleeve 6 is a finger-wheel 12, which is hollow and adapted to surround the various planet-gears, to be herein-after described. A gear-wheel 13 is secured by a feather 14 to the sleeve 6, so as to rotate therewith. Projecting to the right of the finger-wheel 12 is a second finger-wheel 15, which is mounted loosely upon the platen-shaft 4 and has secured to the inner face thereof a disk 16, that carries a laterally-projecting headed stud 17, which constitutes a pivotal bearing for a carrier 18, that is recessed at 19 to form a bearing for coöperation with the pivotal stud or pin 17. This carrier is likewise provided near one end with a slotted bearing 20 for the reception of a shaft 21 of the differential planet-gears 22 and 23, which are connected to rotate together by a pin 22^x. That end of the carrier 18 which is on the opposite side of the pivotal bearing 19 is apertured at 24 for the reception of one end of a spring 25, and the opposite end 26 of this spring is bent to form a hook-like bearing, as shown in Fig. 4, that coöperates with a stud 27, that projects from the disk 16. The flexion of the spring 25 tends to maintain the planet-gears 22 and 23 in close engagement with their co-operating gears 8 and 13, so that no lost motion or backlash will take place in the movement of the gears. From an examination of Fig. 2 it will be observed that the disk 16 closes the open end of the finger-wheel 12, so that the various planet-gears are entirely in

- closed by the finger-wheel 12 and the disk 16, and there is no liability of the gears becoming disarranged in the manipulation of the machine, and the parts are maintained free 5 from accumulating dust and present a neat appearance. The line-spacing wheel 10 is provided on its periphery with ratchet-teeth 28, with which a line-spacing pawl 29 coöperates. The pawl 29 is pivotally connected at 30 to one 10 arm 21 of a two-arm line-spacing lever, which is pivoted to the platen-frame at 32. The other arm 33 of this two-arm lever is provided with a finger-piece 34, by means of which it may be vibrated, the parts being restored to 15 the normal position by a coiled spring 35, which is secured at one end to the platen-frame and at its opposite end to the two-arm line-spacing lever. The line-spacing pawl 29 is provided with a depending arm 36, which is 20 adapted to abut against a piece 37, which is pivoted to the platen-frame at 38 and is provided with three faces 39, against any one of which the depending arm abuts when the parts are in the normal position, depending upon 25 the position to which the piece 37 has been moved or rotated around its pivot 38, it being understood that suitable means are provided to retain the piece in any one of the three positions to which it may be adjusted. In this 30 manner a change in the extent of throw of the line-spacing lever and pawl is effected in order to turn the line-spacing wheel one, two, or more teeth, as determined by the positioning of the piece 37, and in the feed movement of 35 the pawl 29 the depending arm 36 abuts against and is limited by a pin 36^x, carried by the arm 31. This arm 31 likewise carries a rigid locking-pawl 31^x, which at the limit of the feed movement of the pawl 29 will be brought 40 into engagement with the teeth of the line-spacing wheel 10, thus locking it against further rotation.
- Coöperating with the peripheral teeth on the line-spacing wheel 10 is a roller 40, which 45 is supported by a spring 41, that is secured at 42 to the platen-frame and which presses the roller against the teeth. This spring-pressed roller 40 tends to maintain the line-spacing wheel against accidental displacement.
- 50 In the operation of the device for ordinary line-spacing a rotation will be given to the line-spacing wheel 10 by the spacing-lever, and a corresponding rotation will be transmitted to the platen 2 by reason of the fact 55 that the various gears are in mesh, and the gears 22 and 23 will revolve bodily with their coöperating gears and with the finger-wheel 12. Should the operator desire to provide a differential spacing—that is to say, provide a 60 rotating movement of the platen which differs from that which may be attained with the line-spacing wheel 10—it is merely necessary to rotate the finger-wheel 15, which will cause the disk 16 to be rotated with it, thus carrying 65 the differential gears 22 and 23 around their

coöperating gears 8 and 13, which is effective to rotate the gear 22 around its shaft 21 by reason of the engagement of this gear with the gear-wheel 8. This rotation of the gear-wheel 22 will cause a corresponding rotation of the gear-wheel 23, that meshes with the gear-wheel 13, connected to the sleeve 6, to which the line-spacing wheel 10 is secured. The gear-wheels 22 and 23 being of different diameters, the effect of this movement is to transmit 70 a differential movement between the platen-shaft and the line-spacing wheel 10 or to rotate the platen with relation to the line-spacing wheel when the latter is held against movement. The spring detent-roller 40 is relied upon in order to secure the line-spacing wheel against movement during this rotation of the parts by means of the finger-wheel 15.

The finger-wheel 12 is at all times effective to move the line-spacing wheel 10 and the platen 2 together, all of the parts at this time being moved bodily, as is the case when the line-spacing wheel itself is operated by the pawl 29.

It will be understood that the device for moving the platen with relation to the line-spacing wheel is effective, not only to provide a differential spacing that cannot be attained by the ordinary line-spacing device for filling in partly-printed blanks and the like, but that 90 it is effective to change the various points of impact of the type upon the platen or to distribute the wear, so that the entire surface of the platen may be used and the wear will not be produced at fixed lines thereon. 95

From the foregoing it will be understood that the line-spacing wheel, the differential gearing, and regulating finger-wheel therefor may be located at one end of the platen and outside of the platen-frame; that said device 105 may be situated wholly outside of and extraneous to the platen; that said devices do not occupy any of the space between the end bars of the platen-frame, and that it is unnecessary to reduce the length of the platen to accommodate 110 said devices; that it is unnecessary to provide a special construction of the platen in order to employ the devices, and that they may be readily applied to existing forms of type-writing machines. 115

While I have shown the gear-wheels 22 and 23 as separate wheels that are connected to rotate together, obviously they may be made as a single wheel with different portions thereof having different diameters, and various 120 other changes may be made in the construction and operation of the device without departing from the spirit of my invention.

What I claim as new, and desire to secure by Letters Patent, is—

1. In a type-writing machine, the combination of a line-spacing wheel, a platen-shaft, a platen secured thereto and adapted to be turned independently of the line-spacing wheel, a train of gears coöperating with the

line-spacing wheel and the platen-shaft, and hand-operated means for moving said train of gears to effect a movement of the platen and platen-shaft independently of the line-spacing wheel, the said train of gears, line-spacing wheel and hand-operated means being located at the same end of the platen.

2. In a type-writing machine, the combination of a line-spacing wheel, a finger-wheel rigidly connected thereto, a platen-shaft, a platen secured thereto and adapted to be turned independently of the line-spacing wheel, a train of gears coöperating with the line-spacing wheel and the platen and adapted to rotate bodily therewith when the line-spacing wheel is rotated for regular line-spacing or when said finger-wheel is turned, and hand-operated means for moving said train of gears to effect a movement of the platen and platen-shaft independently of the line-spacing wheel for fractional spacing.

3. In a type-writing machine, the combination of a line-spacing wheel, a platen-shaft, a platen secured thereto and adapted to be turned independently of the line-spacing wheel, a train of gears coöperating with the line-spacing wheel and the platen and adapted to rotate bodily therewith when the line-spacing wheel is rotated for regular line-spacing, hand-operated means for moving said train of gears to effect a movement of the platen and platen-shaft relatively to the line-spacing wheel, and a finger-wheel rigidly connected to the line-spacing wheel for rotating the line-spacing wheel, the gears, the platen-shaft and the platen all together for regular line-spacing.

4. In a type-writing machine, the combination of a line-spacing wheel, a platen adapted to move independently thereof, planet-gears coöperating with the line-spacing wheel and platen, and means for turning the planet-gears to effect a movement of the platen independently of the line-spacing wheel, said line-spacing wheel, planet-gears, and the means for turning the planet-gears being located at one end of the platen.

5. In a type-writing machine, the combination of a platen-frame, a line-spacing wheel, a platen adapted to move independently thereof, planet-gears coöperating with the line-spacing wheel and platen, means for rotating the platen line-spacing wheel and planet-gears together as a whole, and means for turning the planet-gears to effect a movement of the platen independently of the line-spacing wheel, said line-spacing wheel, planet-gears and the means for turning the planet-gears for differential spacing being located at the end of the platen and outside of the platen-frame.

6. In a type-writing machine, the combination of a line-spacing wheel, a platen adapted to move independently thereof, planet-gears coöperating with the line-spacing wheel and platen, a finger-wheel rigidly connected to the

line-spacing wheel and operatively connected to the planet-gears and platen, for rotating them together as a whole, and a finger-wheel for turning the planet-gears to effect a movement of the platen independently of the line-spacing wheel.

7. In a type-writing machine, the combination of a line-spacing wheel, a platen adapted to move independently thereof, planet-gears coöperating with the line-spacing wheel and platen, means for turning the planet-gears to effect a movement of the platen independently of the line-spacing wheel, and spring-pressed means for maintaining a close engagement between various of said planet-gears.

8. In a type-writing machine, the combination of a platen, a line-spacing wheel, a finger-wheel operatively connected thereto, planet-gears contained within said finger-wheel and coöperating with the platen and the line-spacing wheel, and means independent of said finger-wheel for turning the planet-gears to effect a movement of the platen independently of the line-spacing wheel.

9. In a type-writing machine, the combination of a platen, a line-spacing wheel, differential planet-gears coöperating with the platen and the line-spacing wheel, means for turning the planet-gears to effect a movement of the platen independently of the line-spacing wheel, and line-spacing mechanism coöperating with the line-spacing wheel to effect a movement thereof together with the platen, said line-spacing wheel, planet-gears and line-spacing mechanism being located at one end of the platen.

10. In a type-writing machine, the combination of a platen, a line-spacing wheel, a finger-wheel operatively connected thereto, planet-gears contained within said finger-wheel and coöperating with the platen and the line-spacing wheel, means independent of said finger-wheel for turning the planet-gears to effect a movement of the platen independently of the line-spacing wheel, and line-spacing mechanism coöperating with the line-spacing wheel to effect a movement thereof together with the platen, and means for locking said line-spacing wheel against rotation.

11. In a type-writing machine, the combination of a line-spacing wheel, a platen adapted to move independently thereof, a finger-wheel adapted to rotate the platen and line-spacing wheel together, toothed planet-gears coöperating with the line-spacing wheel and platen, said planet-gears being effective to afford a rotation of said finger-wheel, line-spacing wheel and platen together, a second finger-wheel carrying certain of said toothed planet-gears and adapted to rotate the same to effect a movement of the platen independently of the line-spacing wheel, and means for retaining the line-spacing wheel against movement while said second finger-wheel is being rotated.

12. In a type-writing machine, the combination

tion of a line-spacing wheel, a platen adapted to move independently thereof, a finger-wheel adapted to rotate the platen and line-spacing wheel together, toothed planet-gears coöperating with the line-spacing wheel and platen, a finger-wheel carrying certain of said toothed planet-gears and adapted to rotate the same to effect a movement of the platen independently of the line-spacing wheel, movable means for retaining the line-spacing wheel against movement and spring-pressed means for maintaining said toothed gears in close mesh to prevent lost motion or backlash.

13. In a type-writing machine, the combination of a line-spacing wheel, a platen adapted to move independently thereof, a finger-wheel adapted to rotate the platen and line-spacing wheel together, toothed planet-gears coöperating with the line-spacing wheel and platen and surrounded by said finger-wheel, a regulating finger-wheel, a carrier connected to said regulating finger-wheel and carrying certain of said toothed planet-gears and adapted to effect a movement of the platen independently of the line-spacing wheel.

14. In a type-writing machine, the combination of a line-spacing wheel, a platen adapted to move independently thereof, a hollow open-ended finger-wheel, planet-gears contained within said finger-wheel and adapted to coöperate with the platen and line-spacing wheel, and hand-operated means for actuating said planet-gears to rotate the platen independently of the line-spacing wheel, said hand-operated means including a disk which closes the open end of the hollow finger-wheel.

15. In a type-writing machine, the combination of a platen, a line-spacing wheel adapted to move independently thereof, a train of gears coöperating with the line-spacing wheel and the platen, and hand-operated means for moving said train of gears to effect a movement of the platen independently of the line-spacing wheel, said hand-operated means including a pivoted spring-pressed carrier for certain of said planet-gears.

16. In a type-writing machine, the combination of a platen, a line-spacing ratchet-wheel therefor, a finger-wheel rigidly connected to said ratchet-wheel, a gear-wheel which is connected to the ratchet-wheel, and gear connections for operatively connecting the ratchet-wheel to rotate with the platen when said finger-wheel is turned or for effecting a movement of the platen with relation to the line-spacing wheel.

17. In a type-writing machine, the combination of a platen, a line-spacing ratchet-wheel therefor, a finger-wheel rigidly connected to the ratchet-wheel, intermediate differential gearing between said ratchet-wheel and the platen which enables the line-spacing ratchet-wheel and platen to be turned together through said finger-wheel, and means independent of the finger-wheel for transmitting movement

to said differential gearing and thereby effecting a movement of the platen relatively to the ratchet-wheel.

18. In a type-writing machine, the combination of a platen, a line-spacing ratchet-wheel, a finger-wheel rigidly connected to the line-spacing ratchet-wheel for rotating said platen and ratchet-wheel together, a regulating finger-wheel, and a train of intermediate differential gearing between said regulating finger-wheel and the platen, and between the regulating finger and ratchet wheels, whereby a movement of the regulating-wheel is effective to move the platen relatively to the ratchet-wheel, said regulating finger-wheel, line-spacing wheel and differential gearing being located at one end of the platen.

19. In a type-writing machine, the combination of a platen, a line-spacing ratchet-wheel, a finger-wheel rigidly connected to said ratchet-wheel for rotating said platen and ratchet-wheel together, a regulating finger-wheel movable independently of the platen, and a train of intermediate differential gearing between said regulating finger-wheel and the platen and between the regulating finger and ratchet-wheels, certain of said gears being carried by the regulating finger-wheel, whereby a movement of the regulating finger-wheel is effective to move the platen relatively to the ratchet-wheel, said gearing forming an operative connection from the first-mentioned finger-wheel to the platen so that said finger-wheel is effective to turn the line-spacing wheel and platen together.

20. In a type-writing machine, the combination of a platen, a line-spacing ratchet-wheel, a finger-wheel for rotating said platen and ratchet-wheel, a regulating finger-wheel, a gear connected to said ratchet-wheel, a gear connected to the platen, and a gear which is carried by the regulating finger-wheel and coöperates with the other gears to effect a movement of the platen with relation to the ratchet-wheel when said regulating-wheel is rotated, said line-spacing wheel, regulating finger-wheel and gears being located at one end of the platen.

21. In a type-writing machine, the combination of a platen, a platen-shaft to which said platen is secured, a ratchet-wheel loosely mounted on the platen-shaft, a finger-wheel connected to said ratchet-wheel for rotating it and the platen, a gear rigidly connected to the platen-shaft, a gear connected to the ratchet-wheel, a regulating finger-wheel adapted to turn on said shaft, and a gear carried by and adapted to revolve with and to turn relatively to the regulating finger-wheel and which co-operates with the other gears to effect a movement of the platen with relation to the ratchet-wheel when the regulating-wheel is turned.

22. In a type-writing machine, the combination of a platen, a line-spacing ratchet-wheel therefor, a train of differential gears coöper-

ating with the platen and ratchet-wheel, and hand-operated means for operating said gears to effect a movement of the platen with relation to the ratchet-wheel, said line-spacing wheel, gears and hand-operated means for actuating the gears being located outside of the platen and at one end thereof.

23. In a type-writing machine, the combination of a platen, a line-spacing ratchet-wheel therefor, a train of differential gears coöperating with the platen and ratchet-wheel, hand-operated means for operating said gears to effect a movement of the platen with relation to the ratchet-wheel, and independent hand-operated means for turning the ratchet-wheel, platen and gears together to effect the line-spacing movement of the platen.

24. In a type-writing machine, the combination of a platen, a line-spacing ratchet-wheel therefor, a train of toothed differential gears coöperating with the platen and ratchet-wheel, hand-operated means for operating said

toothed gears to effect a movement of the platen with relation to the ratchet-wheel, and a spring for maintaining the gears in close mesh and to avoid lost motion.

25. In a type-writing machine, the combination of a platen, a line-spacing ratchet-wheel therefor, a train of differential gears coöperating with the platen and ratchet-wheel, hand-operated means for operating said gears to effect a movement of the platen with relation to the ratchet-wheel, and a finger-wheel which is connected to the ratchet-wheel and surrounds said gears, for turning the ratchet-wheel, platen and gears together to effect a turning of the platen for ordinary line-spacing.

Signed at Arlington, in the county of Bennington and State of Vermont, this 15th day of November, A. D. 1901.
